(57) **CLAIM**

The ornamental designs for a solar panel housing, as shown and described.

DESCRIPTION

FIG. 1 is a top perspective view of a solar panel housing showing my new design.

FIG. 2 is a bottom perspective view thereof;

FIG. 3 is a top view thereof;

FIG. 4 is a bottom view thereof; and,

FIG. 5 is a back view thereof, a front view, a left view, and a right view thereof being identical to the back view.

The broken line shown in the drawing views is for the purpose of illustrating unclaimed environment only and forms no part of the claimed design.

1 Claim, 5 Drawing Sheets

FIG. 1

FIG. 3

FIG. 4

FIG. 5
